PETER VAN VLAANDEREN, OF PATERSON, NEW JERSEY, ASSIGNOR TO VAN VLAANDEREN MACHINE COMPANY, OF PATERSON, NEW JERSEY, A CORPORATION OF NEW JERSEY

REEL

Application filed May 6, 1930. Serial No. 450,158.

This invention relates to rotating reels around which in certain treatments of fabric with liquid the fabric is trained spirally in "rope" form with its convolutions depending therefrom into the liquid, so that 5 in the rotation of the reel the fabric will be advanced spirally and thus progressively through the liquid. The invention relates more particularly to reels of this class which are used in those treatments where the liquid 10 contains acid and which therefore have their peripheries formed of wood slats which are screwed to the frame of the reel, which is necessarily constructed of metal so as to be both light and strong on account of the 15 considerable length frequently attained by such reels and the weight thereof and of the wetted fabric.

Heretofore the practice in constructing these reels has been to key a number of spiders or heads on an axial shaft with spacing sleeves intervening, then pass tie bars through 20 holes in the several spiders or heads so as to stand bowed or arched outwardly from the shaft, then screw nuts on the ends of the tie 25 bars and thereby draw the spiders and sleeves together and form a practically unitary trussed structure well adapted to carry the intended load notwithstanding the considerable 30 length of the reel, then coat all these parts with a rubber or other acid-resisting composition, and finally secure the wooden slats to the thus-coated spiders by screws.

According to the present invention the construction is, generally stated, as follows: The 35 spiders are slipped on to a shaft and welded in their proper positions. For reinforcing the reel frame against the weight of its load the arched or bowed tie-bars are used but each of these is formed in sections each having 40 its own head or enlargement, and having passed these sections through holes in the end spiders and engaged them in peripheral notches in the intermediate spiders their ends are coupled by turn-buckles which are made 45 to draw them up tight and put the entire frame in a state of tension. All joints where metal meets metal are now welded, whereupon the reel frame is coated all over with 50 the acid-resisting composition. Thereupon

wooden disks are affixed face to face against the spiders and to these the wooden slats are secured.

The objects and results of this construction are as follows: The frame by the welding becomes, in effect, a jointless or integral structure, by which I mean that where any two separately formed parts are made to meet they are by the welding merged and made practically one. Therefore the reel is better 55 adapted than others of its kind to withstand the strains and stresses incident to its use, and what is of as great if not greater concern is that since there can be no movement at any joint of the joined parts with respect to each other the fracturing or breaking of the acid-resisting coating which characterizes the use of other reels of this class is prevented, it being known that once this condition occurs the crevice formed admits 60 acid to the metal, whose destructive action goes on unnoticed until finally the reel collapses. By causing the tie-bars to bear upon the intermediate spiders peripherally thereof instead of to penetrate them the tie-bars, 65 which as noted must be arched, are more readily assembled according to my construction and the area to be coated with acid-resisting composition is reduced. Again, where the spiders are of metal and directly receive 70 the slats it is not possible, by coating with the acid-resisting composition, to prevent the acid reaching the metal at the holes where the screws are introduced to affix the slats to the spiders; this difficulty I avoid by using 75 wooden disks, and these may be affixed to the spiders so that while holes therein are necessary these may be fully protected by the acid-resisting composition. 80

Describing my invention now in detail, in 85 the drawings:

Fig. 1 is a section of the improved reel on line 1—1, Fig. 3;

Fig. 2 is a section on line 2—2, Fig. 1, before the reel frame is coated;

Fig. 3 is a section on line 3—3, Fig. 1, on a smaller scale; and

Figs. 4, 5 and 6 are sections of details at certain points in the structure of the reel, as 95 will appear.

In said drawings, 1 is the axial shaft of the reel, preferably tubular. 2 designates the heads or spiders penetrated thereby, these being here circular disks. 3 designates the tie-bars. All these parts are of metal.

The same as in the usual construction, the tie-bars are bent midway their lengths so that in the completed reel frame they will be bowed or arched from the shaft 1, thus to reinforce the reel frame. The tie-bars penetrate holes in the end spiders, but each of the intermediate spiders has peripheral notches 2a in which the tie-bars rest (Fig. 2). The tie-bars preferably have knobs or heads 3a integral therewith and these are of greater size than the holes in the end spiders which they penetrate, and each tie-bar is made in sections joined together by a metal turn-buckle 3b screwed on said sections.

All the joints where any two parts meet are welded together, as at 4, or where a tie-bar penetrates or engages a spider (Figs. 4 and 5), where a knob 3a abuts a spider (Fig. 4), and where a turn-buckle is screwed on each tie-rod section (Fig. 6), as well as where each spider is penetrated by the shaft. The spiders are first fitted on and welded to the shaft, whereupon the tie-rods are applied and tensioned by their turn-buckles and all joints thus produced are welded.

As a final step in the completion of the reel frame it is covered with a coating 5 of rubber composition so that while the general skeleton form of the frame remains the whole is hermetically encased or sealed within an acid-resisting integument or envelope excepting the end bearing portions 1a of the shaft, which are protected from access of acid thereby by the cone shaped barrier 1b.

There remains the attachment of the wooden slats which form the periphery of the reel. In my construction these are attached to the peripheries of wooden plates or disks which in turn are affixed face to face against the spiders and in the present case are elliptical in form. These disks, 6, are formed in two halves notched at 6a at their meeting edges so as to admit the tie bars in assembling the halves with the frame. They are then secured to the disks by the bolts 7 and to each other edge to edge by bolts 8; where the bolts 7 penetrate the spiders holes are formed therein which are large enough to admit the bolts easily even with the coating 5 lining the holes as shown at 7a in Fig. 5. 6a designates the slats.

Sometimes the fabric undergoes a squeezing or wringing treatment as it leaves the reel, which for this purpose has a pulley on which a squeezing roller rests. This pulley in Fig. 1 is shown in a novel form adapting it to be covered for protection against acid and for attachment to the reel. It includes a cylindrical portion or barrel 9 and annuli 10 and 11 of greater diameter than the barrel

and affixed in any way to its ends, the whole being covered with an acid resisting coating 12. The annulus 11 is of greater inside diameter than the spider 2 at the end of the reel to which this barrel is to be attached, so that it may surround the same and be secured by bolts 13 face to face with the end wooden disks, as shown in Fig. 1.

Having thus fully described my invention what I claim is:

1. A metal frame for a reel of the class described comprising a shaft, spiders on the shaft spaced from each other, and tie-bars tying the end spiders together and engaging the intermediate spiders, each spider being welded to the shaft and each tie-bar welded to each spider and said frame being substantially wholly covered with an acid-resisting integument or coating.

2. A metal frame for a reel of the class described comprising a shaft, spiders on the shaft spaced from each other, and tensioned tie-bars tying the end spiders together and engaging the intermediate spiders peripherally thereof and being thereby held bowed from the shaft, each spider being welded to the shaft and each tie-bar welded to each spider and said frame being substantially wholly covered with an acid-resisting integument or coating.

3. A metal frame for a reel of the class described comprising a shaft, spiders on the shaft spaced from each other and having peripheral notches, and tensioned tie-bars tying the end spiders together and engaging the intermediate spiders in their notches and being thereby held bowed from the shaft, each spider being welded to the shaft and each tie-bar welded to each spider and said frame being substantially wholly covered with an acid-resisting integument or coating.

4. In combination, a metal skeleton reel-frame having spaced spiders arranged in a series lengthwise of and penetrated by the reel axis, said frame being substantially wholly covered with an acid-resisting integument or coating, wood disks attached face to face with and to the spiders, and wood slats attached peripherally of and to the disks.

5. In combination a metal skeleton reel-frame having spaced spiders arranged in a series lengthwise of and penetrated by the reel axis and tie-bars connecting the spiders and spaced from each other around and also spaced from said axis, said frame being substantially wholly covered with an acid-resisting integument or coating, wood disks each formed in sections notched to receive the tie-bars and meeting together edge to edge and secured face to face to a thus coated spider, and wood slats attached peripherally of and to the disks.

6. In combination, a reel of the class described comprising a series of slats forming

the reel periphery and a structure on which the slats are mounted including a metal frame, and a metal pulley including a barrel portion and end-forming annuli attached thereto, said frame and pulley each being substantially wholly covered with an acid-resisting integument or coating, and means to secure said pulley to said structure in concentric relation to the reel axis and with one of said annuli face to face with a part of said structure.

7. A metal frame for a reel of the class described comprising a shaft, spiders on the shaft held spaced from each other, and tie-bars tying the end spiders together and engaging the intermediate spiders peripherally thereof and being thereby held bowed from the shaft, each tie-bar comprising sections and a turn-buckle screwed on the two sections and tensioning the tie-bar.

8. A metal frame for a reel of the class described comprising spiders spaced from each other axially of the reel and tie-bars tying the end spiders together and engaging the intermediate spiders, each tie-bar being welded to each spider and said frame being substantially wholly covered with an acid-resisting integument or coating.

9. A metal frame for a reel of the class described comprising spiders spaced from each other axially of the reel, and tie-bars tying the end spiders together and engaging the intermediate spiders peripherally thereof and being thereby held bowed from the axis of the reel, each tie-bar comprising sections and a turn-buckle screwed on the adjoining ends of said sections and tensioning the tie-bars.

In testimony whereof I affix my signature.

PETER VAN VLAANDEREN.
